UNITED STATES PATENT OFFICE.

JOHN D. DAILEY, OF WHITE PLAINS, NEW YORK.

DEVICE FOR LOWERING OR RAISING SMOKE-STACKS.

SPECIFICATION forming part of Letters Patent No. 627,844, dated June 27, 1899.

Application filed February 24, 1899. Serial No. 706,681. (No model.)

To all whom it may concern:

Be it known that I, JOHN D. DAILEY, of White Plains, in the county of Westchester and State of New York, have invented a new and Improved Device for Operating Smoke-Stacks or Masts, of which the following is a full, clear, and exact description.

This invention relates to improvements in devices for operating smoke-stacks or masts for steam vessels. To permit of a steam vessel passing under a bridge or the like, it is often found necessary to lower the stack or mast or a portion thereof. This is generally a difficult operation, requiring considerable time and labor.

The object of my invention, therefore, is to provide a simple means for lowering a smoke-stack or mast and means for automatically returning it to its normal position after passing under a bridge or the like.

I will describe a device for operating smoke-stacks or masts embodying my invention and then point out the novel features in the appended claims.

Reference is to be had to the accompanying drawings, forming a part of this specification, in which similar characters of reference indicate corresponding parts in both figures.

Figure 1 is a partial side elevation and partial section on the line 1 1 of Fig. 2 of a device embodying my invention, and Fig. 2 is a section on the line 2 2 of Fig. 1.

Referring to the drawings, 1 designates a fixed portion of a smoke-stack, and 2 a swinging portion. The swinging portion 2 has a hinge connection 3 with the section 1, and, as here shown, the two sections have a lap-joint 4.

Mounted in bearing-blocks 5, arranged on the roof 6 of a vessel, is a rock-shaft 7, and secured to this rock-shaft 7 are arms 8, from which links 9 extend to a connection with a ring 10, attached to the swinging section of the smoke-stack. Also connected to this rock-shaft 7 are grooved wheels 11, from which chains 12 extend downward into wells or cylinders 13, here shown as secured in the vessel. To the end of each chain 12 is secured a sliding block 14, and surrounding the chain between said block 14 and the fixed cover 15 of the well or cylinder is a spring 16.

On each end of the rock-shaft 7 is a lever 17, by which the device is to be operated to lower the section 2 of the smoke-stack. In operation when it is desired to lower the section 2 of the stack the rock-shaft 7 is to be operated by the levers 17. This will cause the section 2 of the stack to be moved substantially to the position indicated in dotted lines in Fig. 1, and at the same time the spring 16 will be compressed, so that after passing underneath a bridge and upon releasing the levers 17 the spring 16 by expanding will rock the shaft 7, and consequently by counter-balancing the stack will move the stack-section 2 to its normal or upright position, and any sudden jar of said section against the section 1 will be prevented by lugs 18, extended from the rock-shaft 7, engaging with lugs 19, extended from the inner bearing-blocks 5.

While I have shown the stack-section 2 as having two link connections with the rock-shaft, it is obvious that one will answer the purpose, and it is also obvious that a single spring having a chain connection with a single wheel 11 will make an operative device, and instead of using two levers 17 a single one may be employed. While I have described the device as applied to a smoke-stack, it is obvious that it may be applied to masts and the like.

Having thus fully described my invention, I claim as new and desire to secure by Letters Patent—

1. A smoke-stack or mast, comprising a fixed section, and a swinging section, a rock-shaft having connection with the swinging section, means for operating the rock-shaft and means for returning the swinging section to normal position, substantially as specified.

2. A smoke-stack or mast, comprising a fixed section and a swinging section, a rock-shaft, a connection between said rock-shaft and the swinging section, a lever extended from the rock-shaft, and a counterbalance having connection with the rock-shaft for moving the swinging section of the stack to its normal position, substantially as specified.

3. A smoke-stack for a vessel, comprising a fixed and a swinging section, a rock-shaft mounted on the vessel, a lever extended from said rock-shaft, a grooved wheel on said rock-shaft, a well or cylinder, a spring in said well

or cylinder, and a connection between the grooved wheel and the lower end of said spring, substantially as specified.

4. A smoke-stack for a vessel, comprising
5 a fixed section and a swinging section, a rock-
shaft on the vessel, arms extending from said
rock-shaft, link connections between said
arms and the swinging section of the stack,
10 levers extended from the rock-shaft, grooved
wheels on said rock-shaft, cylinders arranged
in the vessel, springs arranged in said cylin-
ders, chain connections between the grooved
wheels, and blocks engaging with the lower
ends of the springs, substantially as specified.
15 5. A smoke-stack, comprising a fixed sec-

tion and a swinging section, a rock-shaft,
arms extended from said rock-shaft, link con-
nections between said arms and the swinging
section of the stack, levers extended from said
rock-shaft, springs having connection with 20
the rock-shaft to automatically return the
swinging section of the stack to its normal
position, and means for limiting the move-
ment caused by said springs, substantially as
specified.

JOHN D. DAILEY.
